STEP TREAD

Rudolph Hovan Hocutt, Charlotte, N. C., assignor
to Southern Friction Materials Company, a cor-
poration of North Carolina

Application June 21, 1945, Serial No. 600,758

1 Claim. (Cl. 20—79)

1

This invention relates to step coverings such as step treads and step nosings, and to other similar fittings such as moldings and the like.

A number of composition materials are available having adequate wear resistance and non-slip properties for use as step coverings. Such materials are well adapted for this purpose, particularly from the standpoint of cost. Difficulty has been encountered, however, in using these materials for step treads and the like because no practical method of equipping the step treads with a nose portion has heretofore been developed.

A nose portion for step treads is desirable not only to provide a complete protective covering for the step, but also to avoid the accident hazard inherent in a step covering having an exposed forward edge which is likely to work loose under the constant daily use to which steps are normally subjected.

The problem of equipping a step tread with a nose portion is complicated by the fact that steps are commonly installed in a variety of shapes and sizes. The usual procedure in view of this difficulty has been to provide a standard form of nose portion which requires working of the forward edge of the step to fit this form. This procedure is costly and inconvenient.

Moreover, in using composition materials as step coverings it is not possible to form an integral nose portion without employing a substantial forming radius, usually of the order of twice the thickness of the material being used. As a result, unless the forward edge of the step is worked to fit this forming radius, it is difficult to position the step covering so that the forming radius does not ride the forward edge of the step and prevent secure attachment of the covering to the step by raising the flat portion of the covering from the top surface of the step near the forward edge.

These difficulties are overcome according to the present invention by providing a universal type of nose portion for step coverings which will fit any of the various shapes and sizes of steps commonly in use. An important feature of my invention is the manner of forming the nose portion in the nature of a flange integral with the flat portion of the step covering and with the outer edge of the nose portion disposed substantially in underlying relation to the point on the flat portion at which the forming radius for the nose portion begins. This construction provides a nose portion arranged to engage the front

edge of a step of any of the usual shapes or sizes in line contact so that no working of the forward edge of the step is necessary to fit the nose portion. Also, by disposing the nose portion in underlying relation to the flat portion of the step covering the forming radius is positioned beyond the edge of the step and the flat portion will lie properly on the top surface of the step.

Another important feature of my invention is that the above described construction provides a method of adapting relatively inexpensive composition materials for use as step treads and the like. In preparing step treads according to the present invention, for example, I may use a composition fabric material of the type disclosed in the copending applications of Snow, Serial No. 467,620, filed December 2, 1942, now U. S. Patent No. 2,424,861, and Serial No. 602,426, filed June 29, 1945, which comprises a fabric material impregnated with a thermosetting resin composition, cured to harden and set the impregnant, and then surface abraded to remove the hard and brittle impregnant curing crust and render the impregnated fabric material relatively flexible and smooth and gripping. Composition fabric materials prepared in this manner have excellent wear resistance and friction properties and are particularly well fitted for use as step covering material. These composition fabric materials are adapted for use according to my invention by a sizing treatment with a penetrating thermosetting resin solution which takes a relatively rigid set so that the nose portion can be set under the influence of heat substantially in place when formed.

Other composition materials may also be used if desired. Any impregnable material, for instance, which has been treated to fill up and body the material and invest it with adequate wear resistance and non-slip properties, and which may be formed and set under the influence of heat, may be used according to the present invention.

My invention is illustrated in the accompanying drawing in which:

Fig. 1 is a perspective view of a step tread formed according to my invention;

Fig. 2 is a diagrammatic sectional view of a step fitted with a step tread of this type;

Fig. 3 is a corresponding sectional view illustrating the use of a nosing formed according to my invention;

Fig. 4 is a fragmentary sectional view illustrating a manner of forming the nose portion of step coverings; and,

Fig. 5 is a diagrammatic representation of the manner in which the formed step coverings are arranged for final heat treatment.

As illustrated in Fig. 1, my invention comprises a step covering of the step tread type, which includes a flat portion 10 adapted to be attached in covering relation on the top surface of a step, and a nose portion 11 integral with the flat portion 10 and adapted to be disposed over the forward edge of the step. The nose portion 11 is formed in the nature of a flange along an edge of the flat portion 10, and as previously mentioned the outer edge of the nose portion 11 is disposed substantially to underlie the point on the flat portion 10 at which the forming of the nose portion 11 begins. That is, the flange formed by the above noted construction of nose portion 11 is disposed with an underlying angularity with respect to the flat portion 10, and this underlying angularity is provided in a degree sufficient to extend the outer edge of the flange underneath the flat portion 10 beyond the point on the flat portion 10 at which the forming of the nose portion begins, as described more in detail below.

The above described construction of the step covering is further illustrated in Fig. 2, which is a diagrammatic representation of the manner in which such a step covering is fitted to a step. In Fig. 2, the step is shown at 12; the usual risers being indicated at 13. The step 12 is commonly formed at its forward edge with a rounded nose as at 14, although in practice there is no standard shape of nose 14 and its form is apt to vary considerably from one installation to another. Also, the steps 12 are used in various widths and thicknesses. To provide a step covering which may be readily fitted to any of the various sizes and shapes of steps, it is accordingly necessary to arrange the step covering so that it may be fitted and adequately secured to the step without reference to the size or shape of the step. This result is accomplished according to the present invention by arranging the nose portion 11 so that it engages the nose 14 of the step only in line contact (as at 15 in Fig. 2), and by further disposing the nose portion 11 to underlie the flat portion 10 of the step covering so that the forming radius (or formed area adjacent the flat portion 10) of the nose portion 11 is positioned clear of the step nose 14 and thus has no tendency to disturb the engagement of the flat portion 10 with the top surface of the step 12.

As previously noted, a substantial forming radius is required for composition materials, which the present invention contemplates using as step coverings. A general rule is that the forming radius should be at least twice the thickness of the material being formed. Unless this large forming radius happens to fit the form of the step nose 14 exactly, it is apt to ride the nose 14 so that the flat portion 10 of the step covering is raised from the forward portion of the top surface of the step 12 and cannot be properly secured to the step 12. If the flat portion 10 of the step covering is fitted by forcing it into contact with the top surface of the step 12 under these conditions, the nose portion 11 is sprung to a protruding position so that it constitutes an accident hazard. This problem would not arise with a completely rigid material such as metal, or with a fully flexible material such as rubber, but these materials have disadvantages for use as step covering, such as lack of proper friction properties in the case of metal and aging in the case of rub-

ber, and they are relatively expensive so that there is accordingly considerable advantage in providing a means for using the less expensive and specially adapted composition materials.

In forming step coverings according to the present invention, the difficulty occasioned by the large forming radius necessary with composition material is avoided by constructing the nose portion 11 so that the forming radius is spaced from the nose 14 of the step 12 and does not affect the manner of fitting the step covering on the step. This construction provides a universal type of nose portion 11 so that the step coverings may be manufactured in standard sizes without regard to the particular step on which they are to be installed.

The flat portion 10 with which the nose portion 11 is integrally formed, may also be made in standard tread sizes. Usually it is not necessary for the step covering to fit all the way to the rear riser 13 because the wear on the step 12 is encountered in the forward area and adequate protective covering of this portion is all that is needed. When complete covering is desired, however, in an instance where a standard size does not fit exactly, the next larger standard size may be cut down, or a nosing constructed according to the present invention with a rear filling of some covering material such as linoleum might be used, as illustrated in Fig. 3.

In Fig. 3, the nosing comprises a flat portion 16 which is of relatively short width but of sufficient surface area to allow secure attachment of the flat portion 16 on the top surface of the step 12, and an integral nose portion 11 constructed as described above. A nosing of this sort may be used to provide a wear resistant and non-slip protective covering for the forward portion and nose of a step in combination with a covering for the rear portion of the step of some standard floor covering material as indicated by the dotted lines in Fig. 3.

As previously mentioned, step coverings may be constructed according to my invention from the composition fabric materials disclosed in the above identified copending applications. These materials comprise a fabric material bodied with a thermosetting impregnant composition (which is cured in situ), and surface abraded to remove the crust of hardened impregnant (which forms during curing) and condition the composition fabric materials with desirable surface characteristics.

In using materials of this type to form the step coverings of my invention, the composition material after being cut to suitable step covering dimensions is sized in a thermosetting resin solution which takes a relatively hard set. Most any of the water soluble phenolic resins, for example, may be used for this purpose. The sizing treatment may be suitably carried out by dipping the composition fabric material in the sizing resin, running the sized material through squeeze rollers to remove excess resin, and then allowing the sized material to air dry for about 24 hours. After sizing the composition fabric material is ready for the step of forming the step covering nose portion.

The forming operation may be carried out as illustrated in Fig. 4. I have found that a form made up of plywood sections or the like gives very satisfactory results. The form illustrated in Fig. 4 comprises an upper 17 and a lower 18 body section spaced by interposed blocks 19. A forming slot 20 is provided by shaping an edge

of the upper section 17 and related spacing block 19 to give the form of nose portion 11 desired, and then arranging a corresponding toe block 21 to complete the forming slot 20.

Forming of the nose portion 11 is accomplished by inserting an edge of the sized composition fabric material cut to step covering dimensions in the forming slot 20, as indicated by the dotted lines in Fig. 4. The extending portion of the material being formed is then pressed over so that it lies flat on the upper section 17 and is weighted in place. Usually, the forming operation will be facilitated by heating the composition fabric material for a short period just prior to forming. Heating at 250° F. for about 15 minutes will give satisfactory results in most cases.

The forming means described above is particularly well adapted for use with composition materials because it will allow the material to form according to its natural characteristics. Composition materials, particularly materials of the type described in the above mentioned pending applications, are apt to vary to some degree in forming characteristics from piece to piece. In the case of composition fabric materials, for example, different characteristics are presented depending upon whether the form is effected lengthwise or across the weave of the base fabric. Slight differences in thickness or internal structure will also affect the manner in which the material forms. As a result, difficulties are often experienced in forming composition materials by forcing them to the shape of a given form because the above mentioned variations will not as a practical matter allow exact uniformity of forming and if such uniformity is attempted, a high percentage of rejects results. The forming means of the present invention avoids this difficulty by allowing the composition material freedom during forming. That is, the composition material 10 is allowed to assume the form to which it is best adapted over the form block composed of the upper body section 17 and interposed block 19, and is only held in place along an edge portion by the retaining or toe block 21 during forming. This arrangement allows a consistent underlying angularity for the nose portion 11 to be obtained without encountering the difficulties which would result if the composition material were restricted at the forming radius during forming.

Weighting of the formed step coverings in place may be accomplished by superimposing the forms as illustrated in Fig. 5. The forms are advantageously built up in tiers in this manner on a truck or dolly or the like, with a final weighting member 22 placed over the top form, so that they may be readily disposed in a curing oven to set the resin sizing. A cure at 200° F. for about 24 hours is usually required to harden the sizing sufficiently to set the formed nose portion 11 in place. After treatment in this manner the step covering may be removed from the forms and a finish applied if desired.

The step coverings may be installed on a step with a cement of the waterproof type. The cement is applied to the surface of the step and also

to the back of the step covering, and allowed to air dry for a few minutes until it becomes tacky. The step covering is then pressed down firmly on the step with the nose portion 11 in contact with the nose of the step. As noted above, only line contact with the nose of the step occurs so that the installation may be carried out without regard to the form of the nose.

In forming a nose portion 11 for step coverings according to the present invention, I have found that an underlying angularity for the nose portion (as represented by the angle A in Fig. 4) of about 30° is more or less optimum. If this angle is lessened, the underlying disposition of the nose portion 11 tends to be inadequate, and a greater angle provides an excessive spacing of the forming radius from the nose of the step and thus causes the nose portion 11 of the step covering to protrude unduly.

The depth of the nose portion 11 will vary somewhat with the forming radius necessary for the composition material being used. In general the depth should be about four times the forming radius. This ratio, in combination with the underlying angularity of 30° mentioned above, will in most cases dispose the nose portion 11 to underlie the flat portion 10 (or 16) of the step covering adequately in accordance with the present invention.

While the present invention has been illustrated and described with respect to its application in forming step coverings, it will be understood that it is also applicable in other similar instances, such as in forming moldings and the like, and that such similar applications are contemplated within the scope of the appended claim.

I claim:

A step covering formed of relatively rigid, inherently resilient thermosetting resin-impregnated fabric material comprising a flat tread portion and a flanged nose portion adjacent one side edge, said nose portion having a flat flange portion projecting downwardly from and parallelly underlying the tread portion at substantially a 60° angle and a curved portion interconnecting the tread and flange portions, and said curved portion having a radius of at least twice the thickness of the resin-impregnated fabric material from which the step covering is formed.
